UNITED STATES PATENT OFFICE.

SAMUEL CHALIKIAN, OF PHILADELPHIA, PENNSYLVANIA.

TOY GUN.

1,218,169.

Specification of Letters Patent.

Patented Mar. 6, 1917.

Application filed February 23, 1916. Serial No. 79,997.

To all whom it may concern:

Be it known that I, SAMUEL CHALIKIAN, a citizen of the United States, and a resident of Philadelphia, in the county of Philadelphia and State of Pennsylvania, have invented certain new and useful Improvements in Toy Guns, of which the following is a specification.

This invention relates to toy guns, and has for its objects the production of a gun either in the shape of a pistol for the amusement of children, or in the form of a musket for marching clubs, the gun being adapted, when fired, to eject, unfold and display an umbrella, parachute and like objects adapted to display various mottoes and insignia, such as the Stars and Stripes.

With the above and related objects in view, my invention comprises the construction, combination and arrangement hereinafter described, an embodiment whereof is illustrated in the accompanying drawing, and is embraced within the scope of the appended claims.

25 In the said drawing:—Figure 1 is an elevation, partly in section, of my improved pistol carrying an unfolded umbrella; Fig. 2 is a sectional view of the barrel showing the umbrella telescoped; Fig. 3 is a plan view 30 of a spider adapted to unfold the umbrella ejected by firing the pistol, and Fig. 4 is a section on the line 4—4 of Fig. 1.

Referring more particularly to the drawing for a detail description of my invention:—5 represents the stock, 6—the barrel, 7—the trigger, 8—the trigger guard, 9—the hammer and 10—the anvil.

The forward end of the barrel is provided with an annular shoulder 11, and the rearward end is provided with an annular shoulder 12, the barrel being also slotted longitudinally at 13.

14 represents a cup-shaped head mounted to slide along the bore of the barrel, said head being provided with a handle shown to be projected through the slot of the barrel. 45 15 represents a rod carried by the head 14, which rod is provided with a hook 16. 17 represents ribs which are shown to be pivotally connected with the rod 15 at its forward end, and 18 represents the covering. 50 19 represents a collar slidably mounted on the rod 15, which collar is provided with a

circular flange adapted to butt-up against the shoulder 11. 20 represents braces pivotally connecting the ribs 17 with the collar 19. The collar 19 carries a spider provided with flexible legs 21 provided with ways adapted to bear against and to guide the braces 20 as shown in Figs. 1 and 2. 22 represents a helical spring wound upon the rod and connecting the head 14 with the shoulder 11.

Inside the stock 5 is pivoted a lever provided with an arm 23 engaged with the trigger 7 and with an arm 24 provided with a hook adapted to engage the arm 25 of the hammer 9. 26 represents a flat spring adapted to actuate the arm 24 to engage the arm 25. 27 represents a pin carried by the arm 25, and 28 represents a flat spring engaging 70 the pin 27. 29 represents a catch pivotally connected with the arm 24 and adapted to slide between the shoulder 12 and the head of a rivet 30.

From the above description the operation 75 of the gun will be readily understood to be as follows:—Referring to Fig. 1, when the head 14 is pulled from its full line position to its dotted position, the hook 16 is forced over the catch 29, as shown. The rod 15, 80 during its rearward movement, first carries the umbrella downwardly over the barrel until the pivoted ends of the ribs strike the collar 19 which is thereby forced downwardly of the rod. The downward movement of the collar, forces the braces 20 through the annular shoulder 11, whereby they are forced to swing into vertical positions thereby forcing the ribs 17 to swing into vertical positions, and the umbrella is 90 inverted, folded and telescoped as shown in Fig. 2, with the spring 22, and the legs of the spider 21 under tension. When the trigger 7 is moved from its full line position into its dotted position, the arm 23 is 95 forced upwardly, causing the arm 24 to pull the catch 29 downwardly, releasing the hook 16. The spring 22 is now free to contract and to pull the head 14 into its full line position. The umbrella is thus forced outwardly of the barrel, and the spider legs being under tension force the braces to swing outwardly, and the ribs are forced to unfold the umbrella.

When the trigger is pulled with the hammer in its full line position, the arm 24 is

forced to release the hammer arm 25, and the spring 28 forces the hammer into its dotted position.

When the trigger is released, the spring 26 forces the arm 24 upwardly and the arm 23 forces the trigger into its full line position.

To get the pistol ready for firing, the hammer is forced from its dotted line into its full line position, causing its arm 25 to swing frontwardly and to become engaged with the hook of the arm 24, the pin 27 forcing the spring 28 into its full line position.

From the above it will be understood that, with the hammer in its dotted position, the umbrella may be either telescoped or ejected without firing the pistol; with the umbrella in its open position, the pistol may be loaded and fired without the umbrella being disturbed; and when the umbrella is telescoped and the hammer in its full line position, the pistol may be fired and the umbrella ejected at the same time.

Having thus described my invention, what I claim as new and desire to protect by Letters Patent, is—

1. In combination with a gun provided with a longitudinally slotted barrel, a rod 30 slidingly mounted in the barrel and provided with a handle projecting through the slot, said rod provided with a hook at its rear end and ribs extended from its front end, a collar slidably mounted on the rod, braces 35 pivotally connecting the ribs with the collar, a spider provided with yieldable legs pressing against the braces, a catch adapted to engage the hook, a trigger adapted to actu-

ate the catch to release the hook and means adapted to force the rod outwardly of the 40 barrel when the hook is released.

2. In combination with a gun-barrel, an umbrella adapted to be invertedly telescoped therein, a rod pivotally connected with the umbrella-ribs and provided with a hook, a 45 catch adapted to engage the hook when the umbrella is telescoped, a trigger adapted to actuate the catch to release the hook, means adapted to force the umbrella outwardly of the barrel, and means adapted to unfold the 50 umbrella.

3. In combination with the barrel of a gun provided with a trigger, an umbrella adapted to be telescoped inside the barrel, 55 means adapted to force the umbrella outwardly of the barrel, means adapted to unfold the umbrella, a catch adapted to restrain the ejecting means, said catch being adapted to be actuated by the trigger to release the ejecting means.

4. In combination with the barrel of a gun provided with a trigger, an umbrella provided with means for inverting it and to telescope it inside the barrel, means to eject the umbrella outwardly of the barrel, means 65 to unfold the ejected umbrella, means to restrain the ejecting means, said restraining means being adapted to be actuated by the trigger to release the ejecting means.

In testimony whereof I have signed this 70 specification in the presence of two subscribing witnesses.

SAMUEL CHALIKIAN.
